Application June 17, 1936, Serial No. 85,630

15 Claims. (Cl. 229—43)

This invention relates to containers and more particularly to containers of the type which are fabricated from a plurality of formed blanks comprising fibrous materials, metal foil and the like.

One of the objects of the present invention is to provide a novel container which is made, at least in part, of fibrous materials and which is impervious to air and moisture.

10 Another object is to provide a novel, impervious container which may be readily opened without the aid of tools or sharp instruments.

In the art of packaging tobacco and particularly cigarettes, an art in which the present invention is especially useful, it has been found desirable to pack comparatively large numbers of the latter, such as fifty cigarettes, in a comparatively flat container. Heretofore these containers have been made of rigid metal, such as 15 tin, or telescoping paper containers have been employed. Such containers as are now in use are not impervious to either air or moisture and accordingly permit tobacco or other contents to dry out under some climatic conditions and to become 20 too saturated with moisture under other conditions. The metallic boxes have proved the more satisfactory of those heretofore provided, but they are heavy and rigid and the sharp corners thereof render them undesirable to carry and 25 detrimental to one's attire.

It is accordingly a further object of the invention to provide a container which satisfies the above requirements while obviating the objections to the prior container.

30 Another object is to provide a novel container which is yieldable, will readily vend its contents, and is sufficiently rigid to prevent crushing in normal usage, and one which is inexpensive and lends itself to volume manufacture.

35 A still further object is to provide a novel method and means for applying a closure and/or closures to the container by welding the same in position.

The above and further objects and novel features of the invention will more fully appear from 40 the following detailed description when taken in connection with the accompanying drawings. It is to be expressly understood, however, that the drawings are for the purpose of illustration only 45 and do not constitute a definition of the limits of the invention, reference being had primarily for this latter purpose to the appended claims.

In the drawings, wherein like reference characters refer to like parts throughout the several 50 views,

Fig. 1 is an isometric view of one form of container embodied in the present invention;

Fig. 2 is an elevation of the back of the container;

Fig. 3 is an isometric view showing the cover 5 in raised position and the primary closure partly removed;

Fig. 4 is a similar view showing the container partly in section, the section being taken on a line 10 parallel to the front face of the container;

Fig. 5 is a detail top plan showing one corner 15 of the container body;

Fig. 6 is a sectional view, on an enlarged scale and with parts broken away, the section being 20 taken on line 6—6 of Fig. 3;

Fig. 7 is a sectional view, with parts broken away, showing one form of means for forming the container body, the section through the latter being taken on line 7—7 of Fig. 5;

Fig. 8 is a sectional elevation view, with parts 25 broken away, illustrating suitable means for drawing grooves and complementary ribs in the side walls of the container body;

Fig. 9 is a sectional elevation view, with parts broken away, showing means for securing a primary closure in the body;

Fig. 10 is an isometric detail view, on an enlarged scale, of one corner of the container, the same being shown partly in section, taken on 30 line 10—10 of Fig. 1 and with parts broken away;

Fig. 11 is a sectional elevation view, with parts broken away, showing means for securing the cover to the container body, the section through the container being taken on line 11—11 of Fig. 1;

Fig. 12 is an isometric view, with parts broken away, of a filler which may be employed in combination with the container of the present invention; and,

Fig. 13 is a side elevation, partly in section and 40 with parts broken away, of a modification of the container body.

The single embodiment of the invention illustrated, by way of example, is shown in the form of a flat container in which fifty cigarettes may 45 be packed and preserved without loss or absorption of moisture for an indefinite period irrespective of temperatures and humidity or changes in atmospheric pressure. The container is constituted by a plurality of formed, as distinguished 50 from folded blanks, of fibrous materials which may be laminated with metal foil, cellulose acetate, or other suitable materials, each blank in its formed condition being seamless and treated with laminated material to render the same im- 55

5 pervious to air and moisture. Broadly speaking, the container comprises a body drawn from a single blank and a novel primary closure secured therein in an impervious manner, said closure preferably being constructed to permit easy and systematic opening of the container. A pivoted cover which is firmly secured to the body and constitutes a secondary closure therefor may also be provided.

10 The specific form of the container which is illustrated comprises a body 15 that is constituted by a single blank, the marginal portions of which are drawn into flanged relation with the central portion thereof. Body 15 is substantially rectangular in shape with the corners thereof slightly rounded to thereby avoid the detrimental effects of sharp corners on one's pockets in which the container is carried, this also facilitating the drawing operation. The blank from which said body is made consists preferably of an inner lamina 15a (Fig. 10) of fibrous material, such as fiber-board, and an outer lamina 15b of cellulose acetate which may be rendered semi-plastic by the application of heat thereto. Said cellulose acetate lamina is preferably applied to blank 15a before the deformation of the latter in the form of a thin sheet by means of an intermediate bonding stratum of a suitable flexible adhesive.

15 A very thin cellulose acetate lacquer has been found suitable as an adhesive for the above purpose, the solvents in said lacquer being effective to render the cellulose acetate sheet somewhat tacky and the solids thereof serving as a binding medium for the fibrous and acetate lamina. This lacquer may not be readily activated by heat, and therefore the laminated stock may be deformed in heated dies without stripping the acetate from the board. One solvent adhesive which has been found satisfactory for the above purpose contains about 20% solids including some resins and a plasticizer. The acetate lamina 15b may be colored by adding a suitable pigment thereto in order to prevent the appearance of the adhesive film therethrough, and the same may have any suitable printed matter impressed thereon, if desired. In addition to adding to the pleasing appearance of body 15 and rendering the same impervious to air and moisture, cellulose acetate lamina 15b serves the further purpose of counteracting the inherent forces which tend to return the fibrous material 15a to its original blank form after deformation of same and thereby assists in rendering the deformations in the blank permanent in a manner to be more fully pointed out hereafter.

20 Blank 15a, 15b, after being cut to the desired shape for forming body 15, is subjected to a drawing operation adapted to be carried out by suitable cooperating male and female die members whereby the marginal portion of the blank is drawn into flanged relation with the central portion thereof to form the smooth and seamless side walls of the container body and the central portion of the blank is embossed to increase the rigidity thereof. One suitable means for forming blank 15a, 15b in the desired manner is illustrated in Fig. 7 wherein the parts are shown in positions assumed in the completion of the deforming operation. Although the walls 0 of body 15, as well as other parts of the container, are shown in all views, with the exception of Fig. 10, as being formed from a single thickness of material, it will be understood that the same may be and preferably are laminated in the manner above described.

25 In the operation of the die mechanism of Fig. 7, the blank from which body 15 is to be formed is placed in the dotted line position shown with the marginal portion thereof resting on the upper surface of female die 16 and with the central portion thereof contacting the upper surface of a spring mounted buffer die 17, which is reciprocable within said female die. A male die 18, 19, the central portion 19 of which constitutes a stripper for removing body 15 from portion 18, 10 is then moved downwardly into contact with the blank. A peripheral bead 20 on the lower face of die 18 first engages the blank and presses a portion thereof into a peripheral groove 21 in the face of buffer die 17, thereby forming an external lip 22 therein which is effective to give additional rigidity to the body without destroying the flexibility thereof and to prevent warping or sagging of the bottom of same. Upon further downward movement of die 18, 19, which 20 is yieldingly resisted by buffer die 17, the marginal portion of the blank is drawn into the space between the periphery of die 18 and the inner surface of die 16, said marginal portion being yieldingly held against wrinkling or buckling during this drawing operation by a pressure member 23.

25 It will be noted that the surface area of the marginal portion of the blank in the rounded corner is reduced somewhat when the same is 30 drawn into flanged position, and it accordingly becomes necessary to make provision for the excess material at said corners during the drawing operation in order to prevent buckling or tearing of the material. For this purpose the 35 outer wall of die 18 is tapered inwardly from the face thereof at the corners to thereby gradually increase the width of the space between the same and die 16 and thus permit a gradual thickening of the flange, as indicated in Figs. 40 5 and 7, the greatest excess of material in the corners of the blank being at the upper edge of the flange. As the margin of the blank is drawn into die 16 from beneath pressure member 23, the marginal material at the corners is 45 compressed along the arc thereof in a horizontal plane and the thickness of the wall gradually increases as permitted by the inclination of the wall of die 18. By permitting the wall to thicken, excessive compression and consequent 50 brittleness of the fibrous material is avoided and a smooth, seamless flange, constituting the side walls of body 15, is formed.

55 When a laminated blank comprising a lamina 15b of cellulose acetate is employed in forming body 15, the forming or drawing dies are preferably heated in any suitable manner, such as by steam or electricity. Heat is then conducted from the dies to the blank which is being drawn and is effective to render the fibrous materials 60 thereof more pliable and accordingly more susceptible to deformation without buckling or shearing. The heat also renders the acetate sheet 15b plastic, thereby permitting the deformation of the same without setting up stresses 65 in the internal structure thereof and without danger of destroying the bond between the acetate and fiber laminae. Upon the removal of body 15 from the heated dies, the acetate lamina is adapted to set quickly in deformed position when allowed to cool and, since the same is free from internal stresses, it is effective when set to hold the deformed fiberboard under stress and against any tendencies of the same to spring back toward its original position. If desired, 70 75

body 15, upon removal from the heated dies, may be deposited in cold transfer dies whereby lamina 15b is quickly cooled and permitted to set while being mechanically transferred to desired positions.

The formation of body 15 is completed by drawing an external groove and complementary rib 25 in the back wall thereof and two similar ribs 26 and an external bead 27 in the front wall thereof, all for purposes to appear hereafter. One suitable means for drawing said ribs and bead comprises a contactable segmental female die, one segment 28 of which is shown in Fig. 8, and a segmental expansible male die 29, only one segment of which is illustrated. A reciprocal core member 30 is provided for expanding the male die, and suitable complementary ribs 31 and grooves 32 for forming the desired deformations in body 15 are provided on the segments of dies 28 and 29.

To give further assurance of the imperviousness of body 15, the inner surface of the same may be coated with a thin, dry film 24 of moisture proof lacquer which, for a purpose to appear hereafter, preferably has potential adhesive qualities and is activatable by heat or a solvent or both. One lacquer which has been found suitable for this purpose is composed of about 65% of such ester solvents as ethyl acetate, butyl acetate, or the like, and such hydro-carbons as toluol, and about 35% of solids which can be readily activated by solvents as well as heat. The solids content is composed of about 25% of low viscosity nitro-cotton, 60% of resins and about 15% of a plasticizer, such as dibutyl phthalate, which may have small quantities of vegetable oils added thereto, if desired. The resins employed may contain some gums, such as ester gum, but usually synthetic resins, which have more constant physical properties than any natural resin, are used. This lacquer is free from tack at room temperatures and under normal conditions of humidity. A lacquer of the above composition is free from tack at temperatures up to about 125° F. and is accordingly not affected by ordinary climatic or room temperatures.

As shown in Fig. 4, a plurality of cigarettes 33 are packed in body 15 in two rows of two layers each, and novel means acting against the ends 50 of the cigarettes are provided for spacing the latter and holding the same against shifting movement within the box. Said means are preferably constituted by three U-shaped members 34 (Fig. 12), one resting in groove 22 at each end of body 15 and one resting in groove 22a in the center of said body. Each of the spacer members 34 is constituted by a laminated blank comprising a fiberboard or like lamina 34a and a lamina of cellulose acetate 34b adhesively secured thereto in a manner above pointed out in connection with lamina 15b of body 15. The blanks thus constituted are bent in the presence of heat to a shape indicated by dotted lines in Fig. 12, the acetate lamina 34b preferably being on the outer side. 65 The acetate sheet, which is rendered semi-plastic by the heat, is permitted to cool and set in this dotted line position to thereby hold the fibrous blank 34a under stress against the inherent tendencies of the fiber lamina to return to a flat position. Spacers 34 are bent to the full line position indicated in Fig. 12 when the same are placed between the cigarettes and the end walls of body 15. The tendencies of said spacers to return to the dotted line position cause the same to exert 70 a yielding pressure longitudinally of cigarettes 33.

Since the surfaces of spacers 34 which are in contact with the tobacco are impervious and moisture repellent, the same will not absorb moisture from the cigarettes and destroy the freshness thereof. Besides holding the packed cigarettes against shifting within body 15, spacers 34 also avoid the loss of tobacco from the same and prevent any foreign matter getting into the cigarettes after the seal to be next described is broken. Additionally, said spacers lend lateral rigidity to the 10 container as well as shouldering support for primary head 35 to be next described.

In order that the completed container will be impervious and thus prevent the escape or entrance of moisture and air from or into the same, 15 and in order that the container may be readily opened when imperviously sealed without the use of tools or the like, a novel head or closure member 35 is provided for body 15. Said closure, in the form shown, is constituted by a deformed 20 laminated blank comprising a fibrous lamina 35a and a metal foil lamina 35b secured to one another by a suitable adhesive. A plurality of tabs 36 are provided at one end of the blank and the latter is compressed or scored along longitudinal 25 lines 37, which lines are in effect continuations of the sides of tabs 36 and form lines of weakness along which closure 35 may be cleanly sheared by pulling on tabs 36 to open the container when it is desired to use the contents. Grooves 37 may 30 be pressed into the laminated blank 35a, 35b without disturbing the inner plane face thereof or, if desired, suitable scores may be provided in the outer surface of lamina 35a prior to the application of foil lamina 35b thereto. 35

Laminated blank 35a, 35b is subjected to a drawing operation in cooperating die members, not shown but similar to those of Fig. 8, whereby the marginal portion of the blank, as determined by disregarding tabs 36, is drawn into a seamless 40 flange perpendicular to the central portion of the blank, the outer dimensions of said flange being substantially the same as the inner dimensions of the upper marginal portion of body 15 above ribs 25 and 26. The upper horizontal 45 ledges of said ribs are preferably flush with the plane of the tops of cigarettes 33 and with the upper edges of spacers 34.

Being thus deformed, closure 35 is inserted into body 15 after the latter is packed and while the 50 same is supported by a supporting die 38 (Fig. 9) in a female die 39 which is provided with suitable heating means, such as electric heating element 40. The lower surface of said closure is seated on the upper ledges of ribs 25 and 26 and 55 on the edges of spacers 34, and the flange portion thereof, the outer surface of which may, if desired, be treated with a suitable solvent capable of activating lacquer film 24, is pressed outwardly by means of a segmental expansible male die 41 60 into intimate contact with the walls of body 15. Lacquer film 24 on the body walls is activated by the heat from element 40 and by a solvent, if the latter is employed, and is pressed into the interstices of the flanges of fibrous blanks 15a and 35a 65 to thereby substantially weld the same together as indicated at 42, thereby forming an impervious joint or seam. The container being thus imperviously sealed, tabs 36 are bent inwardly and downwardly into the position shown in Fig. 10. 70 If desired, the entire inner surface of closure 35 may be coated with a thin, dry film of moisture proofing material, such as the thermoplastic lacquer employed on the inner surface of body 15.

When it is desired to break the seal thus 75

formed, it is necessary only to grasp one of the tabs 36 between one's thumb and finger and pull the same to the right, as viewed in Fig. 4. The initial tension is effective to separate the section 5 of the closure of which said tab is a part from the end wall of the body at the point 42 where the two are adhesively welded together. At the same time the closure is cleanly severed along the score lines 37 which coincide with the edges 10 of the tab to which the tension is applied. A neat opening of predetermined size, as seen in Fig. 3, may thus be readily and quickly made without destroying the appearance and usefulness of the entire closure. The section or strip 15 which is torn away may be completely removed or only partly torn away and bent back into closed position when it is desired to close the container after the contents are partially removed. If a larger opening is required, another or all 20 of the sections of closure 35 may be removed in the same manner as the first.

In addition to closure 35, a secondary closure or cover 43 is preferably provided whereby the contents of the container may be retained there- 25 in after the removal of said first mentioned closure. Said cover is preferably pivotally mounted on body 15 and latch means are provided whereby the same may be yieldingly held in closed position. In the form shown, cover 43 is constituted by a blank, the marginal edges of which are drawn into flanged relation with the central portion thereof in the same manner as above pointed out in connection with the drawing and embossing of body 15, said blank comprising an inner lamina of fibrous material 43a and an outer lamina of cellulose acetate 43b (Fig. 10). In order to increase the rigidity of cover 43, the central portion thereof is shown as being embossed with a wide groove 44 spaced 40 inwardly from its periphery, thereby forming a raised central portion 45 and a peripheral rib 46 which is complementary to an internal groove into which the upper edge of body 15 and the flange of closure 35 are adapted to extend when 45 said cover is telescopically fitted on said body.

Cover 43, as illustrated, is secured to body 15 for pivotal movement thereon by means of a tab or skirt 47 which is formed by cutting away a portion of the rear wall or flange of the cover 50 adjacent the corners thereof, as best seen in Fig. 2, and cementing said tab to the rear wall of body 15. Said tab is provided with a rib 48 adapted to fit into groove 25 in the back wall of body 15, thereby forming means for hinging 55 and anchoring the cover and assisting in preventing its being stripped off during normal usage. The upper corner of groove 48 constitutes a bending line along which the cover is pivoted, there being no cement or adhesive between skirt or tab 47 and the wall of body 15 above rib 48. Preferably, a thin film of thermoplastic lacquer having an affinity for cellulose acetate is provided on the inner surface of said tab and is activated in the process of affixing 60 the cover to body 15 in a manner to appear hereafter.

Latch means for holding cover 43 in closed position and yet render the same readily releasable for pivotal movement to open position are 70 constituted by a pair of internal ribs 49 drawn in the front flange or wall of said cover, which ribs are adapted to extend into the groove that is complementary to rib 26 on body 15 and to be held therein by the inherent resiliency of the 75 material from which the cover is constructed. An

external bead 50 may also be provided on the front face of cover 43 to serve as a grip whereby said cover may be readily pivoted to open position. For supplementing the above described latch means, small arcuate portions 51 of the rear corners of cover 43 are retained when the rear wall of said cover is cut away to form tab 47. Because of the flexibility and resiliency of the material of cover 43, portions 51 do not materially interfere with the opening and closing 10 movement of said cover, but the same do assist in holding said cover in closed position and, due to the pressure with which the edges thereof are resiliently held against the end walls of body 15 when the cover is open, the same also assist in 15 holding the cover in open position. The grooves and ribs 48 and 49, as well as bead 50, may be drawn into the flange of cover 43 in the same manner that ribs 25 and 26 are formed in body 15, that is, by means of cooperating die members 20 similar in construction and operation to those of Fig. 8 which have been heretofore described.

A novel method and means are provided for applying and securing cover 43 to body 15, said means, in the form shown, comprising a pair of 25 vertically reciprocable members 52 and 53 having enlarged head portions, the adjacent faces of which are contoured to correspond to the bottom surface of body 15 and the top surface of cover 43, respectively. The central portion of 30 the faces of said members are perforated or constructed in the form of a grate, and chambers 54 and 55, which communicate through passages 56 and 57, respectively, with a suitable source of suction (not shown), are provided in members 52 and 53. Body 15, after the same is packed and closure 35 sealed therein in the manner heretofore described, is placed on member 52, and cover 43, which is adapted to be held against the face of member 53 by the force of suction 40 from chamber 55, is moved into telescopic relation therewith by the converging movement of members 52 and 53. When the latter members have reached the desired position, as seen in Fig. 11, a sealing iron or die 58 guided by the marginal 45 portions of said members is pressed against the outer surface of tab 47, the pressure thereof being resisted by a similar member 59 which is moved into engagement with the opposite face of the container. When pressure is thus exerted 50 on the container, the same is prevented from buckling by the longitudinal rigidity of spacers 34 and by the fact that the upper and lower surfaces of the container are held by means of suction in firm engagement with the faces of members 52 and 53. 55

Suitable heating means, such as electric heating element 60, are provided in sealing iron 58 whereby the thermoplastic coating on the inner surface of tab 57 is activated and pressed into 60 the interstices of the engaging surfaces of said tab and the back wall of body 15 to thereby substantially weld the same together. Dies 58 and 59 are provided with ribs which extend into external grooves complementary to ribs 48 and 49 65 and, if desired, the latter ribs may be formed by the pressure of said dies during the process of affixing cover 43 to body 15.

A modification of the body which may be employed in carrying out the present invention is 70 illustrated in Fig. 13. As shown, a body 15', constituted by a blank having the marginal portions thereof drawn into a perpendicular flange, has the bottom thereof embossed to form an internal rib 61 adjacent the periphery thereof. Said rib 75

enhances the rigidity of the body and prevents bowing or sagging of the bottom wall thereof. To further enhance the rigidity and to provide a smooth surface in the bottom of the body, a 5 filler 62 having a thickness comparable to the height of rib 61 is inserted in the bottom of body 15' with the edges thereof in contact with the inner vertical portion of rib 61.

There is thus provided a novel fibrous container 10 and method of fabricating the same from a plurality of blanks, which container is impervious to both air and moisture and embodies a novel closure whereby an opening may be readily and cleanly made therein without the aid of tools, a 15 knife or the like. The container provided is not only of very light weight per unit volume but is also sufficiently rigid to avoid crushing in ordinary use and yet sufficiently flexible to permit the same to be comfortably carried on one's person 20 without danger of damaging his attire. The invention also provides a container which may be readily and inexpensively manufactured from a small number of parts and which has a pleasing appearance. The container provided is particularly 25 useful for packing cigarettes and novel means are employed in combination therewith for protecting the cigarettes against damage and contamination. Additionally, a novel method and means are comprehended for assembling the 30 various parts of the fabricated container.

Although only a single embodiment of the invention has been illustrated and described in detail, it is to be expressly understood that the same is not limited thereto but that various 35 changes may be made therein without departing from the spirit and scope of the invention. For example, the blanks from which the various parts are made may be constituted by one or more thicknesses of material, the material being chosen 40 with regard to the particular use for which the container is desired to be put. Various other changes in the size, shape and design of the container illustrated may also be made as will now be apparent to those skilled in the art. For a 45 definition of the limits of the invention, reference will be had primarily to the appended claims.

What is claimed is:

1. A container comprising a body constituted by a blank having the marginal portion drawn 50 into flanged relation with the central portion thereof, a flanged closure member inserted in the open end of said body and adhesively secured therein, and a cover for said body constituted by a blank having the marginal portion drawn into 55 flanged relation with the central portion thereof and adapted to telescopically receive said body.

2. A container comprising a body constituted by a blank having the marginal portion drawn into flanged relation with the central portion 60 thereof, a flanged closure member inserted in the open end of said body and adhesively secured therein, a cover for said body constituted by a blank having the marginal portion drawn into flanged relation with the central portion thereof, 65 parts of said last named marginal portion being cut away to provide a tab thereon, and means for adhesively securing said tab to said body whereby the cover may be pivotally moved relative to said body.

70 3. A container comprising a body constituted by a deformed blank including fibrous materials, a closure member including fibrous materials secured in said body for imperviously sealing the same, and a cover for the sealed end of said body, 75 said body and cover having cooperating deforma-

tions therein constituting latch means for yieldingly holding said cover in closed position.

4. A container comprising fibrous materials and including a seamless body constituted by a deformed blank, a flanged closure for said body 5 constituted by a deformed blank, and an adhesive interposed between the upper margin of the inner surface of said body and the external surface of the flange of said closure for securing said closure in the body. 10

5. A container comprising fibrous materials and including a seamless body constituted by a deformed blank, a flanged closure for said body 15 constituted by a deformed blank, an adhesive interposed between the upper margin of said body and the external surface of the flange of said closure for securing said closure in the body, and a cover for said body constituted by a deformed blank and having a portion thereof adhesively secured to said body whereby the cover may be 20 pivotally moved with respect to the body.

6. A container comprising a seamless body having one end thereof open and constituted by a deformed blank including a layer of fibrous material and a layer of moisture resistant material, 25 a flanged closure for said open end constituted by a deformed laminated blank including a layer of fibrous material and a layer of moisture resistant material, and means for adhesively securing said closure to the inner surface of said body. 30

7. A container comprising a body constituted by a blank having the marginal portion thereof drawn into flanged relation with the central portion, and a flanged closure adhesively secured in said body to imperviously seal the same, said 35 closure having lines of weakness impressed therein and a tab portion integral therewith whereby the impervious seal between the closure and body may be destroyed and the closure severed along said lines of weakness to open the container. 40

8. A container comprising a body constituted by a blank having the marginal portion drawn into flanged relation with the central portion thereof, a dry film of thermoplastic, moisture proof lacquer on the inner surface of said body, 45 and a flanged closure in said body, the flange of said closure and the inner walls of said body being joined by said thermoplastic lacquer.

9. A container comprising a body constituted by a blank including fibrous materials and having the marginal portion drawn into flanged relation with the central portion thereof to form side walls, a closure for said body constituted by a laminated blank of metal foil and fibrous materials and having a peripheral portion drawn 50 into flanged relation with the central portion thereof, the flanged portion at one side being of greater width than on the other sides and having the excess width thereof slitted to form a plurality of tabs, said closure having score lines 55 impressed therein and extending across the same as continuations of the sides of said tabs, and means for adhesively securing the flanged portion of said closure to the inner surface of the side walls of said body. 65

10. A container comprising a body constituted by a blank including fibrous materials and having the marginal portion drawn into flanged relation with the central portion thereof to form side walls, a closure for said body constituted 70 by a laminated blank of metal foil and fibrous materials having a peripheral portion drawn into flanged relation with the central portion thereof, the flanged portion at one side being of greater width than on the other sides and hav- 75

ing the excess width thereof slitted to form a plurality of tabs, said closure having score lines impressed therein and extending across the same as continuations of the sides of said tabs, means 5 for adhesively securing the flanged portion of said closure to the inner surface of the side walls of said body, a cover for said body comprising a blank having the marginal portion drawn into flanged relation with the central portion thereof, 10 a portion of the flange being cut away adjacent the ends of one flanged side of the cover to form a tab, and means for adhesively securing said tab to a side wall of said body whereby the cover may be pivoted relative to said body to open 15 and close the same, said cover and body having cooperating deformations therein constituting latch means for yieldingly holding said cover in closed position.

11. A container comprising a body, a flanged 20 closure for said body having lines of weakness impressed therein, means for adhesively securing said closure to the inner surface of said body, and tab means integral with said closure whereby a portion of said closure may be severed from 25 said body and torn along said lines of weakness to open the container.

12. A container comprising a body, a flanged 30 closure adapted to fit into an open end of said body in contact with the inner surface thereof, said closure having a plurality of score lines therein, means in said body and independent thereof for positioning said closure, an adhesive

interposed between said body and closure for securing the latter in the former, and tab means integral with said closure for severing the adhesive seal between said closure and body and tearing said closure along said score lines. 5

13. A fibrous container for cigarettes comprising a body constituted by a blank having the marginal portion drawn into flanged relation with the central portion thereof, and a spacer member constituted by a deformed laminated 10 blank having a lamina of cellulose acetate adapted to exert a yielding pressure against the ends of cigarettes in the body.

14. A fibrous container for cigarettes comprising a body constituted by a blank having the 15 marginal portion drawn into flanged relation with the central portion thereof, a spacer member constituted by a deformed laminated blank having a lamina of cellulose acetate adapted to exert pressure against the ends of cigarettes in 20 the body, a flanged closure positioned in said body by said spacer member, and a thermoplastic adhesive interposed between the flange of said closure and the inner marginal surface of said body for imperviously sealing the closure in 25 the body.

15. A container comprising a body having bottom and side walls, and a spacer member constituted by a deformed laminated blank having a lamina of cellulose acetate adapted to exert a 30 yielding pressure against the contents of the body.

GEORGE ARLINGTON MOORE.
